UNITED STATES PATENT OFFICE.

EMILE MAERTENS, OF PHILADELPHIA, PENNSYLVANIA, ASSIGNOR TO
EDWARD SCHEPPERS AND EMILE SCHEPPERS, OF SAME PLACE.

DESIGN FOR WOVEN FABRIC.

Specification forming part of Design No. **11,561**, dated December 30, 1879; application filed December 8, 1879.
[Term of patent 3½ years.]

To all whom it may concern:

Be it known that I, EMILE MAERTENS, of Philadelphia, Pennsylvania, have produced or invented a new and original Design for a Woven Fabric, of which the following is a specification.

My design for a woven fabric is fully shown in the accompanying drawing, which represents an exaggerated view of a piece of fabric embodying the design, which is of an open-work character throughout, being formed of twisted warps and spaced wefts.

The design comprises parallel stripes A, each composed of a central band, *a*, having a multiplicity of twisted warps, and outer bands, *b b*, each consisting of a single line of warps of a finer character than those composing the central band, *a*.

Irrespective of the colors employed, I claim—

The design for a woven fabric, said design comprising stripes A, each composed of a central band, *a*, having a multiplicity of twisted warps, and outer bands, *b b*, formed by single lines of warps, all substantially as described, and as shown in and by the accompanying drawing.

In testimony whereof I have signed my name to this specification in the presence of two subscribing witnesses.

EMILE MAERTENS.
